UNITED STATES PATENT OFFICE.

EDWARD J. VON PEIN AND ARTHUR G. KRAMER, OF DAYTON, OHIO, ASSIGNEES, BY
MESNE ASSIGNMENTS, TO THE NATIONAL CASH REGISTER COMPANY, OF DAYTON,
OHIO, A CORPORATION OF MARYLAND.

CASH REGISTER.

Application filed May 4, 1925. Serial No. 27,743.

This invention relates to cash registers of the lever key type.

An object of this invention is to provide a simple and inexpensive construction where-
5 by items registered by the keys may be en-
tered simultaneously in one or more total-
izers and a printed record made of each item.

Another object of the invention is to pro-
vide a construction which is readily adaptable
10 to an unlimited number of keyboard arrange-
ments without the necessity of providing a
multitude of yoked actuating frames and
other parts.

With these and incidental objects in view,
15 the invention consists of certain novel fea-
tures of construction and combinations of
parts, the essential elements of which are set
forth in appended claims and a preferred
20 form or embodiment of which is hereinafter
described with reference to the drawings
which accompany and form part of this speci-
fication.

Of said drawings:

Fig. 1 is a transverse sectional view taken
25 to the left of the right side frame with parts
omitted for clearness.

Fig. 2 is a detail view of the totalizer
transfer mechanism.

Fig. 3 is a front elevation of the machine
30 with parts omitted for clearness.

Fig. 4 is a detail view showing the driving
shaft operating mechanism.

Fig. 5 is an enlarged perspective view
showing a part of the registering mechanism.

35 Fig. 6 is a detail view showing the arrange-
ment of the graduated cam slots of a group
of keys for causing a differential movement
of the actuating segment.

General description.

40 Described in general terms, the machine
comprises a series of manipulative devices
such as item keys which actuate mechanism
for entering amounts in one or more total-
izers, and set up type carrying members to
45 print upon suitable record material the
amount entered at each operation of the item
keys.

50 In the present application the keyboard ar-
rangement used for illustrating the invention
is only one of a great number in common
use in various business establishments. In
order to satisfy the demand for all the va-
55 rious keyboard arrangements it is necessary

to provide a great variety and sizes of yoked
actuating frames in machines on the market,
for example, the type shown and described in

Letters Patent No. 876,295 issued to T. Car-
ney on January 7, 1908. In the present con-

60

struction the yoked members have been elimi-
nated entirely so that the adaptation of the

differential actuating mechanism to the va-
rious keyboard arrangements has been

65

greatly simplified. Instead of using yokes,
shafts are used and the actuators are driven

65

by means of segments which are operated
directly by means of the keys cooperating

70

with a rod carried by the segments. The seg-
ments are caused to move in unison by co-

75

operating pinions secured to a shaft. In
order to vary the construction for different

75

keyboard arrangements all that is necessary
is to locate the actuators, segments and the

80

pinions according to the requirements of the
keyboard desired. The rods are loosely

85

mounted between the segments, so that they
too can vary according to the location of the

85

segments. From this it is apparent that with
this improved construction, all the segments

90

and actuators can be standard for all key-
boards and the only varying parts are the

95

rods and drive shafts.

100

Specifically described, the machine com-
prises a plurality of groups of amount or

105

item keys 30 pivoted on a transverse rod 31

110

mounted in the side frames of the machine.
The rear ends of the keys engage a key cou-
pler 32 which swings on trunnions 33 jour-
naled in the side frames of the machine. The

Referring to Fig. 3, it may be seen that the item keys 30 are arranged in three groups, as follows: The right hand group represents cents; the middle group represents dimes; and the left hand group represents dollars. There are nine keys in each of the cent and dime groups, and only two keys in the dollar group. The number of keys in the dollar group may be increased by widening the machine. The key arrangement disclosed herein is by way of illustration only. Any of the well known key arrangements in the art can be used with the mechanism disclosed herein. Each group of keys is provided with gear segments 41 and 42 freely mounted on the rod 43 and maintained in lateral position by spacing collars (not shown). The cents gear segments 41 and 42 are in mesh with pinions 44 fastened to a shaft 45 supported in the side frames of the machine. The gear segments 41 and 42 for the dimes group of keys are in mesh with pinions 46 fastened to a shaft 47, and the gear segments 41 and 42 for the dollar group of keys are in mesh with pinions 48 fastened to a shaft 49.

It should be noted that the segments 41 and 42 are loosely mounted on the shaft 43 and that the rod 40 is freely supported at its ends by the segments 41 and 42. This construction, without the use of the shafts 45, 47 and 49, together with the pinions 44, 46 and 48, would permit these parts to twist out of alignment with each other. However, by using the pinions, each meshing with one of the segments 41 and 42 of a pair, the segments are forced to move in unison and thus prevent any possibility of twisting. In this manner the pinion shafts together with their pinions provide an equalizing mechanism for the segments 41 and 42. As above mentioned, this construction permits a great saving in time in assembling these parts and also a flexible arrangement because the parts are loosely mounted in their respective positions, and therefore, all that is necessary when assembling them is to slide them into place.

The pinion shafts 45, 47 and 49 have also fastened thereto pinions 53, 54 and 55 respectively (Fig. 3), which are in mesh with totalizer actuating segments 56, 57 and 58. A second group of totalizer actuating segments 59, 60 and 61 are in mesh with pinions 62, 63 and 64 respectively. These pinions are fast to the shafts upon which they are mounted. Any number of actuating segments can be used in connection with the mechanism disclosed herein, thereby making it possible to actuate any number of totalizers desired.

The gear segments 41 and 42 for each group of item keys 30 are locked against movement, unless a key in their respective group is operated. Projecting laterally from either of the gear segments 41 or 42, as the case may be, is a square pin 70 (Figs. 1 and 5), which contacts the end of a hook 71 formed on either

end of a yoke 72 (see also Fig. 3), which is freely mounted upon the rod 31 and held in normal position by a spring 73. When the yoke 72 is in its home position, it engages a projection 74 formed on each of the keys 30. The depressing of any key in a group will immediately move the yoke 72 around the rod 31 in a counter-clockwise direction, removing the hook 71 away from the square pin 70. The unlocking of the gear segments takes place before the graduated cam slots 39 in the keys cause movement of the rod 40 supported in the gear segments.

The gear segments 41 and 42 are positively returned to their home or locked position by a cam 75 (Figs. 1 and 5) engaging a rearwardly extending arm 76 on the gear segments 41 and 42. While the cam slots 39, in the key arms 38 (Fig. 1), will positively move the gear segments first clockwise, and then counter-clockwise, the cam 75 provides an additional means for returning the gear segments to home position. The cam 75 is fast on a driving shaft 77 supported by the side frames of the machine.

The driving shaft 77 is operated by mechanism generally used in this type of machine, and is well known in the art, and therefore only a brief description of this mechanism will be given herein. Referring to Fig. 4, the key coupler 32 carries a pin 78 on which is freely mounted a square block 79 engaging a slot in a driving double rack 80 which cooperates with a pinion 81 secured to the driving shaft 77.

Totalizers.

The items registered by the keys 30 are simultaneously accumulated in two totalizers 87 and 88 (Fig. 3) supported by arms 89, 90, 91, and 92, which are pivotally mounted upon a rod 93, supported at each end by the side frames of the machine. Only two totalizers are disclosed herein, but any number can be conveniently provided. These totalizers have the usual elements found in accumulators of this type, and are well known in the art, and therefore only a brief description of this mechanism will be given herein.

The totalizers are held in lateral position on the rod 93 by any suitable means such as spacing collars or sleeves (not shown).

Each totalizer has three regular accumulating wheels and three over-flow accumulating wheels. The three regular accumulating wheels of the totalizer 87 are actuated by the actuating segments 56, 57 and 58 previously described; and the three regular accumulating wheels of the totalizer 88 are actuated by the actuating segments 59, 60 and 61 previously described.

When the totalizers are in normal position, as shown in Fig. 1, pinions 94 secured to digit wheels 95 of the totalizers are disengaged from the actuating segments. Just

prior to the clockwise movement of the actuating segments, the totalizers 87 and 88 are moved counter-clockwise around the rod 93 to place the pinions 94 in mesh with the teeth 5 of the actuating segments, where they are maintained until the actuating segments have completed their clockwise movement, when said totalizers will again be returned to their normal or disengaged position. The 10 right hand totalizer 87 is positively moved into and out of engagement with the actuating segments by a cam 96 secured to the driving shaft 77 and cooperating with a roll 97 mounted on a bell crank 98, pivotally mounted 15 on a rod 99 supported in the side frames of the machine. An upwardly extending arm 100 of the bell crank 98 is bifurcated at its upper end to engage a pin 105 carried by a downwardly extending arm 106 on the totalizer arm 89 of the right hand totalizer 87. The left hand totalizer 88 is operated in a manner similar to that of the right hand totalizer just described.

The totalizer transfer mechanism is of the 25 reciprocating pawl type used to operate the totalizer wheels of higher order and each wheel is positively operated by a cam 107 (Fig. 2) secured to the driving shaft 77 and cooperating with a roll 108 carried on a bell 30 crank 109 pivotally mounted on the rod 99. An upwardly extending arm 110 of the bell crank 109 is bifurcated at its upper end to engage a pin 111 mounted in a lever 112 pivoted on the rod 93. Pivoted on the upper 35 end of the lever 112, at a point 113, is a spring-pulled transfer pawl 114. The left hand or forward end 115 of the pawl is adapted to engage a ratchet wheel 116, secured to the digit wheel 95 of the totalizer, and carry 40 from a wheel of lower order to a wheel of higher order.

The transfer pawl 114 is normally held in an ineffective position by a pawl 117 having a shoulder 118 engaging a laterally projecting arm 119 on the pawl 114. The pawl 117 is mounted on a rod 120 supported in the arms 89 and 90 of the totalizer and is held in engagement with the transfer pawl 114 by a spring 121. The pawl 117 has a nose 122 which lies in the plane of a trip cam 123 secured to and rotating with the digit wheel 95 of the totalizer. As the digit wheel advances from the nine position to the zero position, the trip member 123 will engage the nose 122 on the trip pawl 117 and move the pawl in a clockwise direction, moving the shoulder 118 away from the arm 119, allowing the transfer pawl 114 to move on its pivot in a counter-clockwise direction, placing the left hand or forward end 115 in a position to engage a tooth of the ratchet wheel 116 so that the totalizer wheel may be advanced one step of movement when said pawl 114 is moved to the left (Fig. 2) by the 55 cam 107, bell crank 109 and lever 112.

The transfer mechanism shown in Fig. 2 may be duplicated for each wheel of the totalizers with the exception of the first or cents wheel where no transfer is needed.

Printer.

70

The items, as they are entered, may be printed upon record material 129 (Fig. 1) by type carriers 130 mounted upon a rod 131 supported in the side frames of the machine. 75 Fastened to the type carriers are pinions 132 which are constantly in mesh with the actuating segments 56, 57 and 58. Impressions may be made from the type carriers by a platen 133 mounted in an arm 134 fast to a 80 rod 135. Legible impressions may be made upon the record material by the platen 133 striking the record material against an inking ribbon 136 which lies between the record material and the type carrier. The impression arm 134 may be operated by hand or by a suitable connection (not shown) with the driving shaft 77.

Operation.

90

The operation of the machine is the same as that of any key lever machine. Keys representing the amount to be registered are pressed downwardly by the operator, and then released to be returned to their home or 95 normal position by the key coupler 32, aided by the spring 73.

While the form of mechanism herein shown and described is admirably adapted to fulfill the objects primarily stated, it is to be 100 understood that it is not intended to confine the invention to the one form or embodiment herein disclosed, for it is susceptible of embodiment in various forms all coming within the scope of the claims which follow. 105

What I claim is:

1. In a machine of the class described, the combination of a totalizer element, a differential actuator therefor, laterally spaced pivotally mounted gear segments to operate the 110 differential actuator, a rod rotatably supported in said gear segments, a plurality of keys engaging said rod to differentially operate the segments, a rotatable shaft, and a set of pinions on said shaft for causing said segments to move in unison.

2. In a machine of the class described, the combination of like denominational totalizers; actuating devices therefor; a plurality of lever keys provided with differentially arranged cam slots having coinciding neutral sections, a set of laterally spaced pivoted gear segments, a rotatable rod normally extending through the neutral sections of said slots and supported at its ends by said gear segments 120 and adapted to be moved different distances by said keys, a rotatable shaft, and a plurality of sets of pinions on said shaft, one of which sets meshes with the set of gear segments to cause them to move in unison, and another of 125 130

which sets causes the like denominational actuating devices to move in unison with said segments.

3. In a machine of the class described, the combination of a plurality of lever keys provided with differential cam slots, a set of laterally spaced pivoted gear segments differentially movable by said keys, a rotatable rod extending through said slots and supported at its ends in said gear segments, a rotatable shaft, a set of pinions secured to said rotatable shaft engaging said gear segments to cause the same to move in unison, a plurality of totalizer elements of the same denomination, a plurality of laterally spaced pivoted actuating segments for the totalizer elements, and a plurality of pinions secured to said rotatable shaft engaging said actuating segments.

4. In a machine of the class described, the combination with a totalizer element; a differential actuator in substantially the same plane with the totalizer element; and a group of laterally spaced keys to drive the actuator differentially; of laterally spaced, pivotally mounted gear segments; a rod supported in and extending between said gear segments; the rod being of sufficient length to be engaged by any of the keys of the group; a shaft journaled in fixed supports; pinions fast on the shaft and meshing with the respective gear segments to cause them to rock in unison; and means on the shaft to drive the actuator.

5. In a machine of the class described, the combination with a totalizer element; a differential actuator in substantially the same plane with the totalizer element; and a group of laterally spaced keys to drive the actuator differentially; of laterally spaced, pivotally mounted gear segments; a rod rotatably supported in and extending between said gear segments, the rod being provided with shoulders at its ends to prevent axial movement of the rod, the rod being of sufficient length to be engaged by any of the keys of the group; a shaft journaled in fixed supports; pinions fast on the shaft and meshing with the respective gear segments to cause them to rock in unison; and means on the shaft to drive the actuator.

6. In a machine of the class described, the combination of a plurality of sets of lever keys; pairs of suitably journaled gear segments, the individual members of each pair being spaced apart from each other; connect-

ing rods extending between and loosely mounted in the individual members of each pair of gear segments, respectively, at points intermediate the tooth portions and the points at which the gear segments are journaled; the sets of gear segments and lever keys being adapted to coact with their respective connecting rods to actuate the corresponding pairs of gear segments; a rotatable transmission shaft for each pair of gear segments; pairs of pinions fast on their respective shafts and spaced apart to constantly mesh with the respective pairs of gear segments, whereby to cause the individual members of any pair of gear segments to rock in unison when a key in the corresponding set of keys is actuated; other pinions fast on each transmission shaft; pivoted actuating segments with which the last-named pinions, respectively, engage; and totalizer wheels operated by the actuating segments.

7. In a machine of the class described, the combination with a series of totalizer elements arranged in relative proximity; similarly arranged actuating segments for the respective totalizer elements, located in substantially the same planes with their respective totalizer elements; and groups of keys to differentially shift their appropriate denominational actuators, the several keys being dispersed relatively to each other; of means to communicate the differential travel of the several dispersed keys of each group to a single actuator corresponding denominational with such group, including a support; a pair of differentially shiftable gear segments spaced apart and mounted to rock on the support; a rod mounted in and extending between the gear segments, the rod being of sufficient length to be contacted by any key in its respective denominational group; and an equalizing mechanism interposed between the pairs of gear segments of the same denomination and their corresponding actuators, comprising a differential rotatable shaft journaled in fixed supports, pinions fast on the shaft and meshing with the respective gear segments of corresponding denomination; and pinions fast on the shaft and meshing with the corresponding denominational actuators.

In testimony whereof we affix our signatures.

EDWARD J. VON PEIN.
ARTHUR G. KRAMER.
